Filed Dec. 23, 1965, Ser. No. 516,028
34 Claims. (Cl. 53—75)

This invention relates generally to handling machines for cardboard shipping cartons and the like. More particularly, the invention relates to an automatic carton handling machine for performing preselected operations on cartons of different height which are successively delivered to the machine in random sequence.

In its broader aspects, the invention provides an automatic carton handling machine having a frame, conveyor means for successively transporting along the frame the cartons to be handled, and a main operating section containing various means, including power driven cyclic means, for operating on each carton advancing along the frame. One important feature of the invention is concerned with a novel infeed gate mechanism for accurately aligning each entering carton with and admitting the carton to the main operating section of the machine in accurately timed relation to the cyclic operating means embodied therein. This infeed gate mechanism is uniquely constructed to progressively arrest each entering carton in such a way that no damage is incurred either by the carton or its contents and to thereafter release the carton for movement to the main operating section in proper timed relation to the cyclic means. In the course of thus arresting and releasing each incoming carton, the infeed gate mechanism also urges the carton against a fixed guide which accurately aligns the carton relative to the following operating section. Another important aspect of the invention is concerned with a novel organization of the machine, whereby the main operating section of the machine is adjusted automatically in response to the height of each incoming carton in such a way as to permit the machine to handle or operate on incoming cartons of different height which are delivered to the machine in random sequence, all without interruption of machine operation for manual adjustment. In this regard, a significant feature of the invention resides in a unique photoelectric sensing means for sensing the height of each incoming carton and a novel elevating means for adjusting the main operating section of the machine in response to the output of the photoelectric sensing means. The machine is also equipped with a novel sensing means for detecting the presence of a carton at the infeed gate and within the operating section and inactivating the machine against automatic adjustment when the gate is not occupied by a waiting carton or the operating section is occupied by an advancing carton.

While the foregoing and certain other features of the invention may be embodied in carton handling machines of various types, the principal application of the invention involves the closing and sealing of cardboard shipping cartons. For this reason, the invention will be disclosed herein in connection with this particular application thereof.

A wide variety of commercial items are handled in cardboard shipping cartons having top and bottom flaps which, in the completed cartons, are folded to overlapping closed positions and adhesively bonded or sealed to one another. In some cases, both the top and bottom flaps are sealed in a single operation after the items to be packaged have been placed in the cartons. In other cases, the cartons are filled after the lower carton flaps have been sealed in a so called bottom sealing machine. Thereafter, the cartons are run through a so called top sealing

2

machine which closes and seals the top carton flaps. The illustrative embodiment of the present invention is such a top sealing machine.

The prior art is replete with a wide assortment of carton closing and sealing machines. Some of these prior machines are designed to handle cartons of only one size or require manual adjustment to accommodate the machines to cartons of different size. Other prior machines adjust themselves automatically in response to the size of each successive carton delivered to the machines. Carton sealing machines of this latter type, then, are capable of closing and sealing, without interruption for manual adjustments, cartons of different size which are delivered to the machines in random sequence. As noted above, the present carton handling machine, or sealing machine possesses this capability of adapting itself automatically to the height of each incoming carton. Moreover, the present automatic machine is vastly superior to the existing automatic machines of this type.

Thus, the existing automatic carton sealing machine, while perhaps satisfactory from the standpoint of their ability to produce sealed cartons, are deficient in many respects. Among the principal deficiencies of these existing machines are their large size, complexity of construction, high cost of manufacture, low operating speed, and their inability to handle or seal cartons containing relatively fragile items, such as produce. The large size and low operating speed of many of the existing carton sealing machines is due, in large part, to the fact that they rely solely on a cold gluing process to seal the carton flaps. The cold glue employed in this process, while producing an adhesive bond of maximum strength between the closed carton flaps, requires substantial time to set sufficiently to retain the flaps in their closed or folded positions. As a consequence, the maximum rate at which cartons may be conveyed through these machines is severely limited. For example, many existing carton sealing machines of this type have a maximum operating speed on the order of twenty cartons per minute. Moreover, these machines require a relatively long compression section for mechanically retaining the adhesively coated carton flaps in their closed positions until the glue on the flaps has fully set. This, in turn, results in a carton sealing machine which has a relatively long overall length and necessitates substantial floor space for its installation.

The improved carton sealing machine of the present invention avoids this deficiency by utilizing a combined hot and cold gluing process for sealing the carton flaps. The hot glue which is applied to the carton flaps sets almost instantaneously and serves as a temporary bond which retains the flaps in their closed positions during setting of the cold glue that is also applied to the flaps. This cold glue, when fully set, provides a final, high strength bond between the flaps. Because of this resort to a combined hot and cold gluing process in the present carton sealing machine, the operating speed of the machine is materially increased and the overall size of the machine is materially reduced.

The complexity of construction and high cost of manufacture of the existing carton sealing machines constitutes a more serious deficiency of these machines. This complexity and high cost is due, primarily, to the relatively complex methods and means employed in these machines for handling the cartons delivered thereto, folding the carton flaps, and effecting the required automatic adjustments necessary to accommodate cartons of different size when delivered in random sequence. Such complexity gives rise to the necessity of frequent servicing, renders the existing machines prone to malfunctioning, and results in reduced service life.

The present improved automatic carton sealing machine is vastly superior to the existing machines from the stand-

points of costs, complexity of construction, maintenance, and service life. This superiority is achieved by virtue of the fact that the machine components which are required to effect timed entrance of the incoming cartons, closing and sealing of the carton flaps, and automatic adjustment of the machine in response to incoming cartons of different height are greatly simplified and uniquely arranged. In this regard, for example, attention is directed to the earlier discussion wherein certain unique features of the invention were pointed out. An additional unique and important feature of the present carton sealing machine resides in a rotary flap folding mechanism for closing certain top flaps of each entering carton and simultaneously positioning other top flaps of the carton in the proper attitude to receive hot and cold glue from following hot and cold glue applicators. According to a further important feature of the invention, this rotary flap folding mechanism, the hot and cold glue applicators, and certain following flap closing means and carton compression rollers are mounted on a floating, vertically adjustable carriage within the main operating section of the machine, which carriage is adjusted automatically in response to the height of each incoming carton, thereby to permit the machine to close and seal cartons of different height which are delivered to the machine in random sequence. The present carton sealing machine, because of its superior construction, possesses a substantially higher operating speed than the existing machines. The present machine, for example, has a maximum carton handling rate on the order of 75 cartons per minute.

As will appear from the ensuing description, the present carton sealing machine is capable of closing and sealing various types of cardboard shipping cartons. However, the illustrated embodiment of the invention is designed particularly for operation on cartons of the type disclosed in Patent No. 3,197,108. These latter cartons are intended to contain produce, such as avocados, and are sealed after the produce is placed in the cartons. In this connection, a significant advantage of the present carton sealing machine resides in its ability to close and seal produce filled cartons of the type shown in the patent without damage to the cartons or their contents.

It is a general object of the invention, therefore, to provide a new and unique carton handling machine of the character described.

Another object of the invention is to provide an improved carton sealing machine for closing and sealing the flaps of cardboard shipping cartons, and the like, such as that disclosed in Patent No. 3,197,108.

Yet another object of the invention is to provide a carton handling or sealing machine of the character described having a main operating section which is automatically adjustable in response to the height of each incoming carton, whereby the machine is capable of operating on or sealing incoming cartons of different height which are delivered to the machine in random sequence, without interruption of machine operation from manual adjustment.

A related object of the invention is to provide a carton handling or sealing machine of the character which is effective to accurately time the entrance into the adjustable, main operating section of the machine of each incoming carton, sense the height of each entering carton, automatically produce the required adjustment necessary to accommodate the operating section to each carton of different height, inhibit the entrance of each carton to the operating section until this section is properly adjusted to receive the carton, and inactivate the machine against automatic adjustment when no carton is awaiting entrance to the operating section as well as when this section is occupied by a carton, thus to avoid damage to the carton and the machine.

A further object of the invention is to provide a carton handling or sealing machine of the character described which has a relatively high maximum carton handling rate.

Yet a further object of the invention is to provide a carton handling or sealing machine of the character described which is uniquely adapted for operating on or sealing incoming cartons filled with fragile items, such as produce.

5 A still further object of the invention is to provide a carton handling or sealing machine of the character described which is relatively simple in construction, economical to manufacture, reliable in operation, requires minimum servicing, has a maximum service life, and is relatively compact in size so as to require minimum floor space for its installation.

Other objects, advantages, and features of the invention will become readily evident as the description proceeds.

10 With these and such other objects in view, the invention consists in the construction, arrangement, and combination of the various parts of the invention, whereby the objects contemplated are attained, as hereinafter set forth, pointed out in the appended claims, and illustrated 15 in the accompanying drawings.

GENERAL MACHINE OPERATION— FIGURES 1, 1A, 1B

As noted earlier, the illustrated carton handling machine of the invention is a carton closing and sealing machine which is designed to close and seal cardboard shipping cartons of the kind disclosed in Patent No. 3,197,108 and illustrated in FIGURES 1A and 1B. These particular cartons are commonly used to package produce, such as avocados and the like. As shown in the latter figures, carton A has a bottom wall B bounded by upstanding side and end walls C and D. Along the upper edges of these walls are hinged, relatively high and relatively low side and end flaps E and F, respectively. The cartons are delivered to the present carton closing and sealing machine after they have been filled with the avocados or other items to be packaged and enter the machine with their side and end flaps standing generally erect, as shown. During movement of the cartons through the machine, the flaps E and F of each carton are folded to and adhesively secured in overlapping closed positions wherein the flaps close the top opening G of the carton.

Cartons of the kind under discussion are made in various heights. The illustrated sealing machine is designed to operate automatically on incoming cartons of two different heights, hereinafter referred to as high cartons and low cartons. As will appear presently, the machine can be set manually for operating on cartons of other heights. In FIGURE 1B, carton A is a high carton and carton A' is a low carton. These cartons are identical except for their height. It is significant to note at this point the the height h_1 of the high carton end flaps F is greater than the corresponding height h_2 of the low carton end flaps F but less than the corresponding height h_3 of the low carton side flaps E. During operation of the present sealing machine, the high and low cartons A, A' are delivered in random sequence to the machine and the latter automatically adjusts itself to accommodate each incoming carton.

Returning to FIGURE 1A, it will be observed that during their travel through the present sealing machine, the entering cartons pass through several successive stations of the machine, to wit an infeed-sensing station, a side flap closing end flap opening station, a gluing station, an end flap closing station, and a compression station. For convenience, only low cartons are shown in FIGURE 1A. Upon arrival of each entering carton at the sensing station, the carton is momentarily arrested and its height is

sensed. At the proper time, the carton is moved to the following side flap closing end flap opening station where the carton end flaps F are folded outwardly to gluing positions and the carton side flaps E are closed. For convenience, this station of the machine will be hereinafter referred to simply as a side flap closing station. After emerging from the side flap closing station, the carton travels through the gluing station wherein the carton end flaps are coated with glue, preferably both hot and cold glue. During subsequent movement of the carton through the end flap closing station, the adhesively coated carton end flaps are folded to their closed positions of overlapping sealing engagement with the previously closed side flap. The closed and sealed carton then passes through the final compression station where the carton is retained under compression sufficiently long to permit the hot glue to set, thus forming a temporary bond between the flaps. Subsequent setting of the cold glue produces a permanent, high strength bond between the flaps. As will appear presently, the side flap closing station, gluing station, end flap closing station, and compression station contain operating means for closing and sealing each carton, which operating means are vertically adjusted in response to the height of each incoming carton to locate these operating means at the proper elevation to operate on the carton.

GENERAL MACHINE ORGANIZATION—FIGURES 1, 1A, 2A, 2B, 3A, 3B

Reference is now made to FIGURES 1, 1A, 2A, 2B, 3A and 3B illustrating the present carton sealing machine 100 in its entirety. The machine comprises a main frame 102 having a left-hand infeed end and a right-hand outfeed end. Spaced along this frame are the several stations referred to earlier, namely an infeed-sensing station 104, a side flap closing station 106, a gluing station 108, an end flap closing station 110, and a final compression station 112. The incoming cartons are transported along the main frame and through these stations by conveyor means 113 on the frame. Stations 106, 108, 110, and 112 together constitute an operating section 100a of the machine. Located over the main frame 102 within this operating section is a vertically adjustable carriage frame 114. Associated with the carriage frame is an elevating means 116 for raising and lowering the carriage frame relative to the main frame and sensing means 117 for sensing the vertical position of the carriage frame. Mounted on the main frame within the sensing station 104 are means 118 for controlling movement of each incoming carton A and A' from the latter station to the following operation section of the machine. As will appear presently, controlling means 118 comprises an infeed gate mechanism including an infeed gate 119 which momentarily arrests each entering carton at the sensing station. Also mounted on the main frame 102 within the sensing station 104 are sensing means 120 for sensing the height of each incoming carton and sensing means 122 (FIGURE 3A) for sensing the presence of a carton at the sensing station. The vertically adjustable carriage frame 114 mounts operating means 124 for operating on, i.e., closing and sealing, each carton passing through the operating section. Operating means 124 include side and end flap folding means 126 within the side flap closing station 106, glue applicators 128 within the gluing closing station 110, and compression means 132 within the compression station 112.

Briefly, in operation of the carton closing and sealing machine 100, the cartons A and A' enter the sensing station 104 in random sequence from a carton packing means (not shown) where the cartons are filled with the avocados or other items to be packaged. Each entering carton is momentarily arrested at the sensing station by the height sensing means 120. The carriage frame 114 is vertically positioned in response to the height of each carton sensed by this sensing means to vertically locate the op-

erating means 124 at the proper elevation to operate on the respective carton. The infeed gate 119 retracts in timed relation to the cyclic movement of certain elements of the flap folding means 126 to release each carton for movement from the sensing station to the following operating section of the machine. As each carton travels through the latter section, the flap folding means 126 within the folding station 106 operate to first fold the carton end flaps F outward to their gluing positions and thereafter fold the carton side flaps E to their closed positions. During subsequent movement of the carton through the gluing station 108, the glue applicators 128 apply stripes S_H and S_C of hot and cold glue to the inner surfaces of the carton end flaps. As the carton then travels through the end flap closing station 110, the end flap closing means 130 fold the end flap to their closed positions. Final movement of the carton occurs through the compression station 112, wherein the compression means 132 retain the carton in compressed position until the hot glue applied to the carton end flaps has set sufficiently to retain the flaps to their closed positions.

CONVEYOR—FIGURES 2A, 2B, 3A, 3B, 6A, 6B

Referring now in greater detail to the carton closing and sealing machine 100 the conveyor means 113 comprises an infeed conveyor 113a within the sensing station 104 and a main conveyor 113b within the following operating section of the machine. Infeed conveyor 113a has a pair of conveyor chains 134 extending lengthwise of the main frame 102 and trained about sprockets mounted on rotary shafts 136, 138 on the main frame. The upper runs of the conveyor chains 134 are disposed above the upper side of the frame 102, whereby the entering cartons within the sensing station are supported on the upper chain runs. Conveyor chains 134 are devoid of drive dogs or cleats so that these chains have only frictional driving contact with the entering cartons. Main conveyor 113b comprises a pair of conveyor chains 140 which straddle and overlap the infeed conveyor chains 134. Conveyor chains 140 are trained about sprockets mounted on rotary shafts 142, 144 on the main frame 102 and mount a number of aligned and uniformly spaced drive cleats 146. The upper runs of the main conveyor chains are substantially flush with the upper runs of the infeed conveyor chains 134, thus to permit movement of the entering cartons from the infeed conveyor 113a to the main conveyor 113b. The infeed conveyor is driven at a higher rate of speed than the main conveyor. The infeed conveyor gate 119 controls the movement of each entering carton from the infeed conveyor to the main conveyor. Mounted on the outfeed end of the main frame 102 is a motor 148 which is driveably coupled by a sprocket chain drive 150 to the main conveyor sprocket shaft 144. The infeed and main conveyor shafts 138, 142 are driveably coupled by a sprocket chain 152 which is trained in serpentine fashion about sprockets fixed on the latter shafts and an intermediate idler sprocket, as shown in FIGURE 2a. Sprocket chain 152 will be referred to again later. At this point, however, it is evident that the infeed and main conveyors 113a, 113b are driven in unison by the motor 148. During operation of the present sealing machine, these conveyors move continuously.

INFEED-SENSING STATION—FIGURES 2A, 3A, 6A, 7-11

Infeed gate mechanism 118 comprises a pair of guide rails 154 and 156 which extend lengthwise of the main frame 102 within the sensing station 104 and at opposite sides of the infeed conveyor 113a. These rails may be mounted for lateral adjustment relative to the main frame, as shown. Rail 154 serves to locate the entering cartons laterally of the main frame relative to the following operating section of the machine. To this end, rail

154 has a predetermined location laterally of the main frame with respect to the operating section. Rail 154 extends substantially the entire length of the sensing station 104 and comprises an angle with an inner upright flange having an inner guiding surface 158. Adjacent the infeed end of the rail is an inner shoe 160 which defines, in effect, a leading portion of the guiding surface 158. This leading portion of the guiding surface is offset toward the opposite guide rail 156 with respect to the remaining, trailing portion of the guiding surface. Infeed guide 156 comprises a pair of upper and lower plates 162 disposed in vertically spaced horizontal planes with the inner edges of the plates aligned to define guiding surfaces 164. The spacing between the guiding surfaces 158, 164 is greater than the length of the cartons A, A¹, measured between their end walls D. It should be noted at this point that the width and length dimensions of the high and low cartons is the same. The spacing between the leading portion of the guiding surface 158 on the guide rail 154 and the guide rail 156 is obviously less than the spacing between the trailing portion of the guiding surface 158 and the guide rail 156.

This spacing between the guide rail 154, 156 is made greater than the endwise dimension of the entering high and low cartons A, A¹ in order to prevent binding of the carton between the rails, even though the carton walls are bowed outwardly to some degree by the carton contents. This, in turn, permits effective driving of the cartons through the sensing station 104 by the frictional driving contact between the cartons and the infeed conveyor chains 134.

The infeed gate 119 operates in the region between the plates 162 of the guide rail 156 and is pivotally mounted on the main frame. This gate comprises a gate stop 166 which is rigidly attached to the outer end of the piston rod 168 of a dashpot 170. The cylinder 172 of this dashpot is located between the guide plates 162 and is pivotally attached at 174 to these plates. Gate stop 166, therefore, is swingable laterally of the machine frame 102 between its extended position of FIGURE 3a wherein the stop projects inwardly beyond the inner guiding surfaces 164 of the guide rail 156 to engage the adjacent, leading corner of each entering carton A, A¹, and a retracted position wherein the stop is disposed outwardly of the guiding surfaces 164 to release the entering cartons. Indicated at 176 is a pneumatic actuator for extending and retracting the infeed gate stop 166. Actuator 176 comprises cylinder 178 which is pivotally attached at one end, by means 180 to the machine frame 102. Cylinder 178 contains a piston having a rod 182 which extends from the opposite end of the cylinder and is pivotally attached to the gate stop 166. At this point, therefore, it is evident that the gate stop 166 is movable generally endwise of the machine frame 102 and that movement of this stop toward the outfeed end of the frame is resisted by the dampening action of the dashpot 170. Connected between the guide rail 156 and the piston rod 182 of the gate stop actuator 176 is a spring 184 which urges the stop toward the infeed end of the frame. As shown best in FIGURE 10, the actuator cylinder 178 contains a spring 186 which is effective to urge the gate stop 166 toward and normally retains stop in its extended position. Leading from the inner end of the actuator cylinder is a hose 188 through which air or other operating fluid under pressure may be introduced into the cylinder 178 for retracting the gate stop 166 against the action of the actuator spring 186.

As will appear presently, the gate stop 166 normally occupies its extended position of FIGURE 3a, wherein the stop is disposed to engage the adjacent, leading corner 70 of each entering carton A, A¹. Accordingly, each entering carton is momentarily arrested at the sensing station 104 by the gate stop 166. As shown in FIGURE 3a, in order for each entering carton to engage the gate stop, it is necessary that the carton be rotated slightly toward the guide rail 156. To this end, there is mounted on the infeed

end of the guide rail 156 a drag shoe 190. The upper surface of this drag shoe is disposed slightly above the upper runs of the infeed conveyor chains 134. Accordingly, the drag shoe engages the bottom wall of each entering carton and thereby imposes a frictional retarding force on the end of the carton adjacent the guide rail 156. This retarding force causes rotation of the carton of the position shown in FIGURE 3a, wherein one leading corner of the carton engages the inner guiding surfaces 164 on the guide rail 156, thus to assure engagement of this corner of each carton with the gate stop 166. As it will appear presently, fluid under pressure is periodically admitted to the actuator 176 to retract the gate stop 166 and thereby release each carton for movement from the sensing station 104 to the following side flap closing station 106. Each such retraction of the gate stop 166 occurs in such a way that the stop remains retracted for a period of time less than that required for each carton to travel past the stop. Accordingly, the gate stop is returned towards its extended position, by the gate stop actuator spring 186, before each carton clears the stop. Each spring return of the gate stop 166 to its extended position, therefore, is effective to resiliently urge the incoming carton, which has just been released by the stop, toward and against the inner guiding surface 158 of the opposite guide rail 154, thus to locate the carton properly for entrance into the following operating section of the machine. It is significant to note at this point that the rear end of the leading guide shoe 160 on the guide rail 154, which end defines the juncture between the leading and trailing portions of the guiding surface 158 on the latter shoe, is spaced in the direction of the infeed end of the machine frame 102 from the gate stop 166 a distance which is less than the width of each entering carton A, A¹ measured between the carton side walls C. As each entering carton released by the gate stop 166 clears the latter juncture, it is urged by the stop against the trailing portion of the guiding surface 158. The leading carton, therefore, is displaced laterally relative to the following incoming carton, thus permitting the gate stop 166 to be fully extended and thereby disposed for proper arresting engagement with the following carton, before the leading carton has completely cleared the gate stop. In this way, arresting engagement of the gate stop 166 with each entering carton is assured.

As noted earlier, the infeed conveyor 113a is driven at a relatively high rate of speed. Accordingly, if the gate stop 166 were not yieldable, impact of each carton against the stop would jar the carton contents. This jarring of the contents is undesirable, in some cases, such as where the contents comprise avocados or other loose items which may be joggled to positions wherein they protrude above the upper surface of the carton. In the present sealing machine, this jarring of each incoming carton, when arrested by the gate stop, is prevented by yielding of the dashpot 170 and the gate stop spring 184 upon impact of each carton with the stop. Each incoming carton, therefore, is arrested gradually, rather than abruptly, by the gate stop.

The sensing means 120 for sensing the height of each incoming carton A, A¹ comprises a light source 192 and a photosensitive receiver 194 which are adjustably mounted on spaced vertical pivot axes on the upper end of a vertically adjustable bracket 196 on the main frame 102. Light source 192 directs a light beam along an optic axis A₀ of the source. The photosensitive receiver 194 has a sensitive axis A_s. Source 192 and receiver 194 are angularly positioned in such a way that these optic and sensitive axes intersect at a point within the path of movement of each entering carton through the sensing station 104, at a height above the infeed conveyor chains 134 such that the light beam from the source 192 impinges only the adjacent end flaps of the entering high cartons A. Accordingly, during passage of each entering high carton A through the sensing station 104, light from the source 192 is re-

flected from the adjacent end flap of the high carton to the photosensitive receiver 194. No light from the source is reflected to the receiver during the passage of the low cartons through the sensing station. Accordingly, the photosensitive receiver 194 generates an output only in response to the arrival of each high carton at the sensing station.

At this point, it is significant to recall that the side flaps E on the entering low cartons A¹ are higher than the end flaps F on the entering high cartons. As a consequence, the side flaps on each incoming low carton intercept the light beam from the light source 192. However, since the side flaps on the low cartons travel through the light beam at an acute angle, no light is reflected from these flaps to the photosensitive receiver 194. Accordingly, as just noted, the receiver does not generate an output signal in response to movement of the low cartons through the sensing station. The illustrated photoelectric sensing means 120, wherein light from the source 192 is reflected to the receiver 194 from the adjacent end flap of each incoming high carton has a distinct advantage over a conventional photoelectric sensing system for this purpose, wherein the incoming cartons travel between the light source and the receiver. Thus, it was found that with such a conventional sensing system, the upstanding side flaps on the incoming low cartons were often bowed in such a way that they presented a sufficient effective frontal area, when viewed edgewise, to completely intercept the light beam and thereby cause the receiver to generate a false high carton signal. This deficiency of the conventional sensing system is avoided in the present sensing system.

For convenience in the ensuing description, the signal generated by the photo-sensitive receiver 194 in response to passage of each high carton A through the sensing station 104 is referred to simply as a high signal. The effective signal (i.e., no signal) produced by the photo-sensitive receiver in response to movement of each low carton A¹ through the sensing station is hereinafter referred to simply as a low signal.

As noted earlier, and hereinafter described in greater detail, the vertically adjustable carriage frame 114 is vertically positioned in response to the height of each incoming carton sensed by the sensing means 120 to locate the operating means 124 on this frame at the proper elevation for operating on the respective carton. However, it is desirable to inhibit such vertical adjustment of the carriage frame 114 when no carton is present within the sensing station 104. To this end, the sensing station is equipped with the sensing means 122 for sensing the presence of each incoming carton at the sensing station. This latter sensing means comprises a switch which is located in the region between the infeed conveyor chains 134 and is mounted on a bracket 196 adjustably secured to a cross member 198 on the main machine frame 102. Switch 122 has a pivoted operating arm 200 disposed for actuation by each incoming carton arriving at the gate stop 166. As will appear presently switch 122 is connected in a control circuit of the machine in such a way that vertical adjustment of the carriage frame 114 can be effected only when the sensing switch 122 is actuated by an incoming carton.

As noted earlier, the gate stop 166 is periodically retracted to release each incoming carton for movement from the sensing station 104 to the following side flap closing station 106. This retraction of the gate stop is effected by admitting high pressure operating fluid, such as air to the inner end of the gate stop actuating cylinder 178 through the hose 188. Hose 188 is connected to a source 202 (FIGURE 10) of high pressure operating fluid through a solenoid valve 204. Valve 204 is controlled, in part, by a switch 206 mounted on the main machine frame 102 adjacent the main conveyor shaft 142. Switch 206 has an operating member 208 which is periodically actuated by a cam 210 on the conveyor shaft 142.

As will appear presently, switch 206 is operatively connected in the control circuit of the machine in such a way that actuation of the switch operating member 208 by the shaft cam 210 is effective to open the valve 204, and thereby cause retraction of the gate stop 166, in the event that the carriage frame 114 is properly vertically positioned to receive the carton A or A¹ currently engaged with the gate stop. On the other hand, if the elevation of the carriage frame does not correspond to the height of the carton currently at the gate stop, the control circuit of the machine inhibits retraction of the stop in response to actuation of the switch 206 by the shaft hand 210. Thus, each incoming carton is retained at the sensing station 104 until the carriage frame 114 has been adjusted to the proper elevation to receive the carton. It is obvious, of course, that since the cam 210 is mounted on the main conveyor shaft 142, the switch 206 is effective to cause periodic retraction of the gate stop 166, and thereby release of the successive incoming cartons for movement from the infeed conveyor 113a to the main conveyor 113b, in timed relation to the operation of the main conveyor. The timing of the machine in this regard is such that each carton is delivered to the main conveyor by the infeed conveyor slightly in advance of the next set of drive cleats 146 on the main conveyor chains 140.

As already noted, the infeed conveyor chains 134 are driven at a higher velocity than the main conveyor chains 140. This is to cause separation of each carton released by the gate stop 166 from the following carton and to effect arrival of the released carton on the main conveyor chains 140 in the proper timed relation to the advancing drive cleats 146 on the latter chains. As will appear presently, it is essential that each carton be transported by the main conveyor 113b through the operating section of the machine in accurately timed relation to the operation of certain of the operating means 124 of this section. To this end, it is necessary to retard each incoming carton delivered to the main conveyor 113b from the infeed conveyor 113a sufficiently to enable the following drive cleats 146 on the main conveyor chains 140 to engage the carton. This retarding of each incoming carton is accomplished by a combined retarding and camming shoe 212 mounted on the trailing end of the carton guide rail 156. As shown best in FIGURE 3a, retarding shoe 212 comprises a metal strap, the left-hand or leading end of which is pivotally mounted on a bearing post 214 secured to and extending between the guide rail plates 162. Operatively connected between the trailing end of the retarding shoe 212 and the guide rail 156 is a spring 216. Spring 216 urges the trailing end of the shoe inwardly toward the opposite guide rail 154 to an extended position wherein the trailing end of the shoe projects inwardly beyond the guiding surfaces 164 on the guide rail 156. Inward extension of the trailing end of the shoe 212 is limited by an adjustable limit stop 218 coacting between the shoe and the guide rail 156, as shown. During movement of each incoming carton from the infeed conveyor 113a to the main conveyor 113b, following retraction of the gate stop 166, the carton passes between the guide rail 154 and the retarding shoe 212. This retarding shoe frictionally retards the carton sufficiently to restrain the carton against movement by the main conveyor chains 140 until the carton is engaged by the following drive cleats 146 on these chains. During this brief interval, the carton simply slides on the main conveyor chains. Subsequent engagement of the following drive cleats 146 on the main conveyor chains with the carton provides a positive driving engagement between these chains and the carton which is effective to drive the carton past the retarding shoe 212 and into the following main operating section of the machine. The retarding shoe 212 serves also as a camming shoe which resiliently urges each carton laterally toward and into guiding contact with the trailing portion of the guiding

surface 158 on the guide rail 154, thereby to properly locate the carton laterally of the machine relative to the operating means 124 in the operating section of the machine.

At this point, it is evident that the incoming cartons are delivered in successive fashion to the infeed-sensing station 104 of the machine and are carried through this station to a position against the extended gate stop 166 by the infeed conveyor 113a. Each carton is momentarily arrested by the gate stop and its height is sensed by the height sensing means 120. At this time, the carriage frame 114 is vertically positioned, by the elevating means 116, to an elevation corresponding to the height of the carton currently at the sensing station. After the carriage frame 114 has been properly vertically positioned to receive the carton currently at the sensing station, the gate stop 166 is retracted, by actuation of the gate stop switch 206, in the proper timed relation to the movement of the main conveyor 113b to effect movement of the carton onto the main conveyor just slightly in advance of the following drive cleats 146 on this conveyor. The entering carton is retarded for engagement with the following cleats, and is urged into guiding contact with the guide rail 154, by the combined retarding and camming shoe 212. In regard to vertical adjustment of the carriage frame 114 to receive each incoming carton, it will be recalled that the photosensitive receiver 194 of the carton height sensing means 120 is effective to generate a high signal in response to the arrival of each high carton A at the sensing station and an effective low signal in response to the arrival at the sensing station of each low carton A¹. It is obvious, of course, that the receiver 194 effectively generates a low signal whenever the sensing station 104 is occupied by a low carton as well as when no cartons are present at this station. As a consequence, in the absence of any means to prevent such action, the machine would tend to drive the carriage frame 114 to its low carton position whenever the sensing station is occupied by a low carton as well as when no cartons are present at this station. To prevent this needless vertical adjustment of the carriage frame, the switch 122 which senses the presence of the carton at the sensing station is operatively connected in the control circuit of the machine in such a way as to inhibit vertical adjustment of the carriage frame except when the sensing station 104 is occupied by a carton, either a high carton or a low carton. Accordingly, the carriage frame is adjusted to its low carton position only in response to arrival of each low carton A¹ at the sensing station.

CARRIAGE FRAME ELEVATING MEANS— FIGURES 2A, 2B, 3B, 6B, 16, 19

The elevating means 116 for the carriage frame 114 will now be described. Extending horizontally across the main machine frame 102, below the upper runs of the main conveyor chains 140, are a pair of parallel shafts 220 which are spaced a distance lengthwise of the carriage frame. Shafts 220 are rotatably supported, adjacent their outward ends, in bearings 222 secured to the under sides of the upper longitudinal frame members 224 of the main frame. The outward ends of the shafts 220 project a distance beyond the sides of the main frame. Rigidly secured to the projecting ends of the shafts 220 are blocks or crank arms 226. Relatively short stub shafts or crank pins 228 are rigidly secured to the crank arms 226 in parallel, eccentric relation to the shafts 220. Crank pins 223 extend outwardly from the crank arms 226 and are rotatably supported in bearings 230 secured to the under sides of lower longitudinal frame members 232 on the carriage frame 114. At this point, it is evident that rotation of the shafts 220 in unison is effective to raise and lower the carriage frame 114 relative to the main frame 102. Shafts 220 are similarly oriented so that the ends of the carriage frame raise and lower simultaneously. It is obvious that the carriage frame 114 is vertically

movable, in response to the rotation of the shafts 220, between upper and lower limiting positions. In the ensuing description, these positions of the carriage frame are hereinafter referred to simply as high and low positions.

Fixed on the shafts 220 are sprockets 234 around which is trained a sprocket chain 236. This sprocket chain has free ends 236a and 236b. Mounted on the main machine frame 102 between the free chain ends 236a, 236b, is a double acting fluid actuator 238 including a cylinder 240 which is secured to the main frame. Movable in the cylinder 240 is a piston (not shown) having a piston rod 242 which extends through opposite ends of the cylinder. The free end 236a of the sprocket chain 236 is secured, by an adjustable coupling 244 to one end of the piston rod 242. The other free end 236b of the sprocket chain 236 is secured to the opposite end of the piston rod 242 by a second adjustable coupling 244. At this point, it is evident that left-hand movement of the piston rod 242 in FIGURE 2b is effective to simultaneously drive the shafts 220 in a direction to elevate the carriage frame 114 from its low position to its high position. Right-hand return movement of the piston rod 242 is effective to lower the carriage frame from its high position to its low position. Travel of the piston rod 242 is limited by engagement of the actuator piston with the end walls of the cylinder 240. Accordingly, the piston and cylinder serve the dual function of limit stop means for limiting vertical travel of the carriage frame 114 to its high and low positions. Preferably, the actuator 238 is provided with cushioning means for cushioning the piston at the ends of its stroke. According to the preferred practice of the invention, during rotation of the shafts 220 to raise the carriage frame 114 to its high position, the crank pins 228 on these shafts rotate slightly past top dead center whereby the weight of the carriage frame tends to retain the latter in its high position. Carriage frame positioning cylinder 240 is supplied with fluid under pressure through solenoid valves 245a which are operated by the control circuit of the machine to raise and lower the carriage frame 114, as explained later.

In the high position of the carriage frame 114, the operating means 124 on this frame are properly positioned for operating on the incoming high cartons A. In the low position of the carriage frame, the operating means are properly positioned to operate on the incoming low cartons A¹. As noted earlier, and hereinafter explained in greater detail, the carriage frame 114 is automatically vertically adjusted to accommodate incoming high and low cartons which are delivered to the machine in random sequence. In other words, the illustrated machine is capable of automatically sealing high and low cartons, only, which are delivered in random sequence to the machine. In some cases, it is desirable to condition the sealing machine 100 to close and seal cartons of some intermediate height. To this end, the elevating means 116 for the carriage frame 114 is provided with an adjustable limit stop 246. Limit stop 246 comprises the threaded shaft 248 which extends longitudinally of the main machine frame 102, adjacent the carriage frame actuator 238. Shaft 248 extends between and is terminally secured to upright frame members 250, 252 of the main frame. Slideable on the shaft 248 is a sleeve 254 mounting a laterally projecting stop arm 256 with a notch 258 which is adapted to fit over the adjacent coupling 244 between the sprocket chain end 236b and the actuator piston rod 242. Threaded on the shaft 248 at opposite ends of the sleeve 254 are nuts 260. It is evident at this point that the sleeve 254, and the stop arm 256 on the sleeve, is adjustable lengthwise of the piston rod 242 by threading the nuts 260 along the shaft 248. During automatic operation of the sealing machine 100, the stop arm 256 is rotated to its retracted position of FIGURE 2b, wherein the arm clears the carriage frame actuator 238 to permit unrestricted movement of

the carriage frame 114 between its high and low positions. When it is desired to adjust the carriage to some intermediate elevation, corresponding to some intermediate carton height, the stop sleeve 254 is axially adjusted to the proper position and the stop arm 256 is rotated to an extended or operative position, wherein the adjacent coupling 244 engages in the stop arm notch 258. The carriage frame actuator 238 is then operated to drive the piston rod 242 to the right, in FIGURE 2b, to a position wherein a jam nut 262 embodied in the adjacent coupling 244 engages the stop arm. Thus, the carriage frame 114 may be vertically driven to any vertical position, between its high and low positions by appropriate positioning of the stop arm 256 axially of the actuator piston rod 242.

For reasons which will become obvious as the description proceeds, it is necessary to inhibit vertical adjustment of the carriage frame 114 when the main operating section of the machine, that is the area below the carriage frame, is occupied by a carton. To this end, the sealing machine 100 is equipped with a sensing means 264 to sense the presence of a carton on the main conveyor 113b. Sensing means 264 comprises a light source 266 adjacent one end of the main conveyor and a photosensitive receiver 268 adjacent the other end of the main conveyor. Light source 266 is mounted on the infeed carton guide rail 154 and is located at one side of the main conveyor. The photosensitive receiver 268 is mounted on the outfeed end of the main machine frame 102 at the opposite side of the main conveyor. Light source 266 directs a beam of light diagonally across the main conveyor to the photosensitive receiver 268 and across the path of movement of incoming cartons thru the operating section of the machine. The light source and receiver are located in such a way that each carton intercepts the light beam from the source continuously from the time the carton enters on to the main conveyor 113b until the carton emerges from the outfeed end of the machine. As will be explained presently, the photosensitive receiver 268 is operatively connected in the control circuit of the machine in such a way that vertical adjustment of the carriage frame 114 is inhibited whenever the light beam from the light source 266 is thus intercepted by a carton on the main conveyor.

As noted earlier, in order to effect positioning of the carriage frame 114 at the proper elevation to accommodate each carton delivered to the machine, it is necessary to sense the current vertical position of the carriage frame. This position sensing function is performed by the sensing means 117, which comprises a switch mounted on an upstanding frame member 270 of the main machine frame 102. Switch 117 has a pivoted operating arm 272 which is disposed for engagement with one lower longitudinal frame member 232 of the carriage frame. The manner in which the carriage frame position sensing switch 117 is operatively connected to the control circuit of the machine will be explained presently. Suffice it to say here that switch 117 has high position contacts (not shown) which close when the carriage frame 114 occupies its high position and low position contacts which close when the carriage frame occupies its low position.

END FLAP OPENING SIDE FLAP CLOSING STATION—FIGURES 1A, 2A, 3A, 9, 12-15, 20, 21, 26

It will be recalled that the operating means 124 on the carriage frame 114 comprise flap folding means 126 for initially folding the end flaps F of each entering carton A and A¹ outwardly to gluing positions and thereafter folding the carton's side flaps E to their closed positions over the top opening G of the carton. Flap folding means 126 include power drive, cyclically movable flap folding means 276 which are effective to initially fold the end flaps of each carton to their gluing positions and thereafter fold the trailing side flap of the carton.

to its closed position. Flap folding means 276 comprise a pair of rotary flap folding heads 278 which are mounted on the carriage frame 114 over the main conveyor 113b and turn on vertical axis spaced laterally of this conveyor. Rotary flap folding heads 278 are rigidly secured to the vertical, rotary output shafts 280, respectively, of a pair of miter gear boxes 282 which are mounted on frame members 284 extending across the upper side of the carriage frame 114. The lower miter box, as the machine is viewed in FIGURE 3a, has a rotary input shaft 286 which extends beyond the adjacent side of the carriage frame and mounts a sprocket 288. Extending between the miter boxes 282 is a drive shaft 290. Miter boxes 282 contain right angle gearing (not shown) which driveably couples the miter box shafts 280, 286, and 290 in such a way that rotation of the input shaft 286 in one direction is effective to rotate the output shafts 280 in unison in opposite directions. As will appear presently, during operation of the present sealing machine, the miter box input shaft 286 is driven in the clockwise direction of rotation, as the machine is viewed in FIGURE 2a. Rotation of the input shaft in this direction drives the output shaft 280 of the lower miter box in FIGURE 3a in the clockwise direction and the output shaft of the upper miter box in a counter-clockwise direction. Accordingly, during operation of the machine, the rotary flap folding heads 278 are driven in unison in the opposite directions of rotation indicated by the arrows in FIGURE 3a.

Mounted on the main machine frame 102, below the upper runs of the main conveyor chains 140 and adjacent the side of the main frame remote from the miter box input shaft sprocket 288, is a relatively short horizontal shaft 292 which extends crosswise of the machine frame 102 and is rotatably supported in combined radial and thrust bearings 294 on this frame. Fixed on the shaft 292 is a sprocket 296. Referring to FIGURE 2a, it will be observed that the sprocket chain 152, which was referred to earlier and drivably couples the infeed and main conveyors 113a, 113b, is trained about the sprocket 296. Accordingly, shaft 292 is driven in timed relation to the main conveyor chains 140. Mounted on the underside of the lower longitudinal frame member 274 of the carriage frame 114, at the side of the carriage frame adjacent the miter box input shaft 286, are combined radial and thrust bearings 298 which rotatably support the outer end of a relatively short horizontal shaft 300 which extends cross-wise of and into the adjacent side of a machine frame 102. Shafts 292, 300 are driveably coupled by an intervening, telescoping drive shaft 302 which is drivably connected to the inner ends of the shafts 292, 300 by universal joints 304. Shafts 292, 300, and 302 are located directly under the miter boxes 282. Fixed on the outward end of the shaft 300 is a sprocket 306 around which, and the miter box input shaft sprocket 288, is trained a sprocket chain 308. Sprocket chain 308 passes around an idler sprocket 310 on the carriage frame 114 and around a sprocket 312 fixed to a horizontal shaft 314 which is rotatably supported in bearing 316 on the carriage frame. Shaft 314 will be referred to again later. At this point, however, it is evident that the miter box input shaft 286 and the rotary flap folding heads 278 are driven in rotation in unison with the movement of the main conveyor chains 140. It is significant to note here that the telescoping drive shaft 302 and the universal joints 304 between this shaft and the shafts 292, 300 accommodate vertical adjustment of the carriage frame 114 without interrupting the drive coupling between and hence the timed operation of the main conveyor chains 140 and the rotary flap folding heads 278.

Referring now to FIGURES 9, 12-15 it will be observed that the two rotary flap folding heads 278 are identical mirror images of one another. Each folding head comprises a side flap folding shoe 318 and an end flap folding shoe 320. Each side flap folding shoe 318

comprises a narrow, elongate metal plate 322 which is disposed in a plane normal to and is generally circularly curved about the rotation axis of the respective folding head. The leading end of this plate is turned upwardly, as shown, and mounts a disc like thrust member 324. Rigidly secured to the plate 322 of each side flap folding shoe 318 is an upstanding bracket arm 326 which is secured, by the illustrated bolt and slot connection, to a vertical, depending arm 328 of a folding shoe mounting bracket 330. The horizontal arm of this bracket is rigidly secured to the output shaft 280 of the respective miter box 282. It is evident at this point, therefore, that the side flap folding shoes 318 has a fixed elevation relative to the carriage frame 114, which elevation may be adjusted, and that these shoes rotate in unison in the opposite directions indicated by the arrows in FIGURE 3a. The two side flap folding shoes are disposed in a common horizontal plane and are angularly oriented about their respective miter box output shafts 280 in such a way that these shoes rotate in unison through the region between the two flap folding heads 278. It will be observed that the side flap folding shoes move in the direction of the outfeed end of the machine as they rotate through the latter region.

The end flap folding shoe 320 of each rotary flap folding head 278 is located diametrically opposite the respective side flap folding shoe 318 and comprises a metal rod 332 which is generally circularly curved about the rotation axis of the corresponding head. The leading end of each rod 332 is bent upwardly, as shown. Rigidly secured to the rod 332 of each end flap folding shoe 320 is an upstanding bracket arm 334 which is secured, by the illustrated bolt and slot connection, to one arm 336 of a generally L-shaped shoe mounting bracket 338. The other arm of each shoe mounting bracket 338 comprises a pair of spaced parallel arm members 340 which straddle a bearing sleeve 342 fixed to the horizontal arm of the respective side flap folding shoe mounting bracket 330. Each end flap shoe mounting bracket 338 is pivotally connected to its respective side flap shoe mounting bracket 330 by a pin 344 which extends through the arm members 340 and bearing sleeve 342 of the respective bracket. It will be observed that the pivot axes of the shoe mounting brackets 338 are horizontally disposed, whereby the end flap folding shoes 320 are vertically movable. Each end flap folding shoe 320 is urged upwardly by a spring 346.

Secured to the underside of the upper carriage frame members 284, which support the miter boxes 282, are circular cams 348. Cams 348 are coaxially disposed relative to the rotation axes of the miter box output shafts 280, respectively. The mounting bracket 338 for each end flap folding shoe 320 carries a roller 350 which rides against the under surface of the adjacent cam 348. It is evident that the springs 346 are effective to yieldably retain the bracket rollers 350 in contact with their respective cams 348. Accordingly, during rotation of the flap folding heads 278, the rollers 350 ride along the under surfaces of the cams 348. As will appear presently, these cams are shaped to vary the elevation of the end flap folding shoes 320 relative to the carriage frame 114 in synchronism with rotary motion of the latter shoes.

As shown in FIGURE 1a, the entering cartons A and A¹ enter the end flap opening side flap closing station 106 with their side and end flaps E, F standing generally erect. The side and end flap folding shoes 318, 320 of the rotary flap folding heads 278 are constructed and arranged, and the rotary motion of these heads is timed relative to the movement of the main conveyor chains 140, in such a way that the end flap folding shoe initially engage and fold outwardly to their gluing positions the end flaps F of each carton passing through the station 106 and thereafter the side flap folding shoes engage the trailing side flap E of the respective carton and fold this flap forwardly to its closed position, as depicted in FIGURE 1a. To

this end, the end flap folding shoes 320 are so angularly oriented about the miter box output shafts 280 that these shafts rotate into engagement with the inner sides of the erect end flaps F on each incoming carton and thereafter urge these flaps laterally outward to their horizontal gluing positions which the flaps occupy at the gluing station in FIGURE 1a. It is evident that since each incoming carton enters the station 106 with its leading side flap E erect, the end flap folding shoes 320 must be elevated above the upper edge of the leading flap until the latter flap clears the shoes, after which the shoes must be lowered to positions behind the leading flap for subsequent outward folding engagement with the carton end flaps. This vertical movement of the end flap folding shoes 320 is accomplished by the cams 348. To this end, the cams 348 are shaped to effect elevation of the end flap folding shoes 320, during one portion of each revolution of the flap folding heads 278, to elevated positions wherein the shoes are located to clear the leading side flaps of the incoming cartons. During the remaining portion of each revolution of the folding heads 278, that is the portion of each revolution in which the end flap folding shoes engage the end flaps of the incoming cartons, the cams are effective to lower the latter shoes to lower extended positions, wherein the shoes are disposed for outward folding engagement with the carton end flaps. In these lower extended positions, the end flap folding shoes 320 are vertically located to position the carton end flaps in the horizontal gluing positions which they occupy at the gluing station in FIGURE 1a.

The side flap folding shoes 318 of the flap folding heads 278 are diametrically opposite their respective end flap folding shoes 320, as already noted, and are oriented in such a way that the side flap folding shoes rotate into engagement with the rear side of the trailing side flap E on each incoming carton passing through the station 106 and thereafter urge this flap forwardly to its closed position as the carton progresses through the station. The circumferential length and fixed elevation, relative to the carriage frame 114, of the side flap folding shoes 318 is such that these shoes are effective to retain the trailing side flap of each incoming carton in its closed position for a given interval of time as the carton progresses through the station 106. The reason for this retention of the trailing side flap of each entering carton in its closed position for a prolonged interval of time will appear presently.

It will be recalled that the carriage frame 114 is automatically adjusted in elevation to accommodate both the high cartons A and the low cartons A¹ when the latter are delivered in random sequence through the machine. The elevations of the side and end flap folding shoes 318, 320 relative to the carriage 114 are initially adjusted in such a way that when this frame occupies its high position, the shoes are disposed for proper folding engagement with the flaps of entering high cartons and when the carriage frame occupies its low position, the shoes are disposed for proper folding engagement with the flaps of entering low cartons.

The carton flap folding means 126 at the side flap closing end flap opening station 106 comprise, in addition to the rotary flap folding heads 278, static side flap closing means 352 which follow the rotary folding heads and serve to close the leading side flap E of each incoming carton passing through the station 106. The side flap closing means 352 comprise a side flap folding or closing shoe 354 which is adjustable mounted on an upper cross member 356 of the carriage frame 314. This shoe is located over the main conveyor 113b, midway between the main conveyor chains 114. Folding shoe 354 is constructed from a metal strap, or the like, which is bent into the arcuate configuration, best illustrated in FIGURE 2a. The upper, leading end 358 of the shoe 354 is bent at right angles, as shown. This end 358 of the shoe 354 is secured to the carriage frame member 356 by means of

a bolt 360 which extends through a slot in the shoe, thus to permit adjustment of the latter in the direction of movement of cartons through the machine. The trailing portion of the side flap closing shoe 354 is disposed in a common horizontal plane with the trailing portions of the side flap closing shoes 318 on the rotary flap folding heads 278. Folding shoe 354, therefore, is disposed to fold the leading side flap E of each incoming carton to its closed position.

Static side flap folding means 352 comprise a pair of outward folding shoes 362 constructed from metal rods which are bent to the arcuate configuration illustrated. Folding shoes 362 have upturned, leading ends which are adjustably secured, by bolts 364, to the carriage frame member 356. Shoes 362 have coplanar horizontal trailing portions which are secured, at their trailing ends to brackets 366 adjustably attached to the carriage frame 114. The adjustable connections between the carriage frame 114 and the leading and trailing ends of the side flap folding shoes 362 permit adjustment of these shoes laterally of the machine to positions wherein these shoes are disposed to engage the closed side flaps E of each carton adjacent the end edges of these flaps. Shoes 362, however, are spaced inwardly from these end edges a distance sufficiently to permit folding of the carton end flaps F to their closed positions of overlapping engagement with the closed side flaps, as hereinafter explained. As shown best in FIGURE 9, the trailing portion of the center side flap closing shoe 354 is located a small distance above the common plane of the trailing portions of the outer shoes 362. Shoes 362, in turn, are vertically positioned relative to carriage frame 114 in such manner that in the high position of this frame, the vertical spacing between the trailing ends of these shoes 362 and the upper runs of the main conveyor chains 140 is substantially equal to the height of the side and end walls C, D of a high carton A. Similarly, when the carriage frame occupies its low position, the vertical spacing between the trailing ends of the shoes 362 and the main conveyor chains 140 is substantially equal to the side and end wall height of a low carton A¹.

It is now evident that as each incoming carton A or A¹ travels through the side flap closing end flap opening station 106, the end flaps F of the carton are first folded laterally outward to horizontal gluing positions, after which the carton side flaps E are folded inwardly to their closed positions over the top opening G of the carton. As noted earlier, the side flap folding shoes 318 on the rotary flap folding heads 278 are constructed and arranged in such a way that they retain the trailing side flap of each carton in its closed position for a period of time as the carton progresses through the station 106. It is now evident that this retention of the trailing side flap of each carton in its closed position is necessary to assure entrance of the flap under the following side flap closing shoes 354, 362. In this regard, it is significant to note that the side flaps of each carton are first engaged by the center side flap closing shoe 354 and, thereafter, by the outward shoes 362. The high and low cartons on which the illustrated carton closing and sealing machine 100 is designed to operate may have side flaps E of various height. The center side flap closing shoe 354 is made adjustable lengthwise of the machine, as described earlier, to permit engagement of this shoe with the trailing side flaps of the entering cartons, before these flaps are released by the rotary side flap folding shoes 318, regardless of the height of the flaps. Thus, if the incoming cartons have relatively low side flaps, it may be necessary to adjust the center shoe 354 toward the rotary flap folding heads 278 to assure engagement of the trailing folding flap with the shoe prior to release of the flaps by the rotary flap folding shoes 318. It is obvious, of course, that the center shoe 354 is effective to initially close the leading side flap of each incoming carton. Final retention of both the leading and trailing

side flaps of the cartons in their closed positions is performed by the outward shoes 362. As shown best in FIGURE 9, the main machine frame 102 is equipped with rails 368 which are located directly below the outward shoes 362 and serve to slideably support the cartons in the region between the main conveyor chains 140, as the cartons travel through the main operating section of the machine.

GLUING STATION—FIGURES 1A, 2B, 6B, 16, 22

Immediately after emerging from the side flap closing end flap opening station 106, each carton enters the gluing station 108, wherein the stripes S_h and S_c of hot and cold glue are applied to the now upwardly facing, inner surfaces of the currently outwardly folded carton end flaps F. The glue applicator means 128 for applying these glue stripes to the carton end flaps comprise a pair of hot glue applicators 370 and a pair of cold glue applicators 372. These applicators are conventional and, therefore, need not be described in detail. Suffice it to say that one hot glue applicator 370 and one cold glue applicator 372 is mounted on each side of the carriage frame 114 in positions to apply stripes of hot and cold glue to the adjacent end flap of each incoming carton as the latter travels through the gluing station. The hot glue applicators 370 comprise applicator rollers 374 which are driveably coupled, by sprocket chains 376, to a shaft 378 extending cross-wise of and rotatably supported on the carriage frame 114 over the hot glue applicators. Shaft 378, in turn, is driveably coupled by a sprocket chain 380, to the shaft 314, described earlier, which is driven in rotation by the sprocket chain 308 which drives the input shaft 286 of the miter boxes 282. The hot glue applicator rollers 374, therefore, are driven in rotation by the main machine motor 148. Rotatably mounted on the upper side of the carriage frame 114 are a pair of drums 382 on which are wound so called glue ropes 384 which feed the hot glue applicators 370, respectively. These hot glue applicators are equipped with means (not shown) for feeding the glue ropes into the applicators, wherein the glue embodied in the ropes is heated to the liquid state and then conveyed to the applicator rollers 374. These rollers, in turn, dispense the hot liquid glue onto the carton end flaps F. The cold glue applicators 372 are supplied with cold liquid glue under pressure and comprise nozzles 388 which are disposed for engagement by the end flaps F of each carton passing through the gluing station. Embodied in the cold glue applicators are normally closed valve means (not shown) which open in response to engagement of carton end flaps with the applicator nozzles 388, whereby the applicators 372 are effective to dispense cold glue onto the end flaps of each passing carton. As shown best in FIGURE 1A, the hot glue applicator rollers 374 and the cold glue applicator nozzles 388 are offset laterally of the machine in such a way as to apply laterally offset hot and cold glue stripes to the end flaps of each passing carton.

Extending lengthwise of the carriage frame 114, directly below the hot and cold glue applicators 370, 372, are a pair of supporting rails 390 which are disposed to support the outwardly folded end flaps F of each incoming carton as the latter travels past the applicators, as shown best in FIGURE 16. Supporting rails 390 are secured to the carriage frame 114 by means of bracket supports 392 which are adjustable to permit adjustment of the supporting rails 390 laterally of the machine. Mounted on the outer side of each supporting rail 390 in the region directly below each cold glue applicator 372, is an additional supporting plate 394. Supporting plates 394 resist downward deflection of the end flaps of each passing carton by the downward pressure of the cold glue applicator nozzles 388, thus to assure opening of the cold glue applicator valve means by the end flaps of each carton. As shown best in FIGURE 16, the hot and cold glue applicators are mounted on the carriage frame 114

by adjustable bracket means 395 which permit adjustment of the applicators laterally of the carriage frame for proper engagement with the end flaps of each carton passing through the gluing station.

- 5   Mounted on the carriage frame 114 are hold down rods 396 which extend from a position in advance of the cold glue applicators 372 to a position between the hot and cold glue applicators. The leading ends of these rods extend upwardly at an angle. The trailing ends of the rods extend horizontally and are spaced above the upper surfaces of the supporting rails 390 a distance substantially equal to the thickness of the carton end flaps F. As shown in FIGURE 16, the hold down rods 396 are disposed outward of the supporting rails. As each incoming carton 10 emerges from the side flap closing end flap opening station 106, the outwardly folded end flaps F of the carton engage the hold down rods 396. These rods then serve to guide the carton end flaps into the regions between the cold glue applicator nozzles 388 and the underlying supporting plates 394. It is evident at this point, therefore, that during movement of each incoming carton through the gluing station 108, the outwardly folded carton end flaps F receive the hot and cold glue stripes S_h and S_c from the hot and cold glue applicators 370, 372. At this time, the 20 side flaps E of each carton are folded to their closed position.

END FLAP CLOSING STATION—FIGURES 1A, 2B, 3B, 17, 23, 24

- 30   Upon emerging from the gluing station 108, each carton enters the end flap closing station 110. As noted earlier, this latter station is equipped with end flap closing means 130 for folding the end flaps of each incoming carton to their closed positions of overlapping engagement with the now closed side flaps of the carton. End flap closing means 130 comprise a pair of flap folding rods 398, or plows as they are commonly referred to. Rods 398 are bent, as shown, and are mounted on the carriage frame in such a way that these rods engage the currently downwardly facing, normally upper surfaces of the end flaps and fold the end flaps upwardly and inwardly to their closed positions, wherein the adhesively coated surfaces of the flaps engage the carton side flaps. As noted earlier, the outward side flap closing shoes 362 are located to engage the side flaps of each carton a distance inwardly of the ends of these flaps, thus to permit folding of the carton end flaps to their closed positions. However, it is desirable to have the outward shoes 362 engage the carton side flaps as close as possible to the ends of these flaps 40 in order to prevent the latter flaps from interfering with closing of the carton end flaps by the end flap closing rods 398.

COMPRESSION STATION—FIGURES 1A, 2B, 3B, 18, 25

- 55   Immediately after emerging from the end flap closing station 110, each carton enters the final compression station 112. The compression means 132 at this latter station comprise a number of pressure rollers 400 which are 60 rotatably supported in frames 402. Each roller frame 402 is mounted, by means 404, for limited vertical movement relative to the carriage frame 114 and is resiliently urged in the downward direction by means of compression springs 406. The roller frames 402 are 65 spaced laterally of the carriage frame 114 in such a way that the compression rollers 400 are disposed to engage the closed end flaps F of each carton emerging from the end flap closing station 110. These rollers, then, exert downward pressure on the end flaps of each carton and serve to mechanically retain the end flaps in their closed 70 positions sufficiently long to permit setting of the hot glue applied to the flaps. As is well known in the art, such hot glue sets almost instantaneously, whereby it is necessary to provide the present carton sealing machine 100 with 75 only a relatively short compression section, as illustrated.

This, in turn, reduces the overall length of the machine. As noted earlier, the hot glue applied to the carton end flaps provide a temporary bond between these flaps and the carton side flaps which retain the flaps in their closed positions during setting of the cold glue on the flaps. This cold glue, when set, provides a permanent, high strength bond between the flaps. Associated with rollers are blades 408 for scraping glue from the rollers.

This completes the structural description of the machine. The control system of the machine referred to earlier, will now be described.

Electrical control system

The automatic carton handling machine as previously described includes, generally speaking, an elongated main frame having conveyor means mounted thereon. A carriage frame is disposed above the main frame within a main operating section of the machine and has means associated therewith for performing an automatic operation upon a series of cartons of differing heights. In accordance with the presently preferred embodiment of the machine the automatic operation consists of sealing the tops of the cartons. However, if desired, the automatic operation could consist of pasting a label on each carton, or such other operation as might be desired.

Another element which is essential to the overall organization of the automatic machine is a means for controlling entry of cartons into the operating section. In the illustrated machine, this controlling means is a gate for controlling entry of the cartons onto a continuously moving main conveyor which transports the cartons through the operating section. Sensing means are preferably provided which are cooperatively associated with this gate for sensing whether a carton is waiting to be admitted through. Additional essential features of the machine are the provision of sensing means for sensing a particular height category in which the waiting carton belongs, and means for selectively raising or lowering the carriage frame relative to the main frame, so as to successively accommodate cartons of the different heights. Preferably, the machine is equipped with means for sensing whether the operating section is occupied by a carton.

Because of the very high speed operation of the illustrated automatic machine of the present invention it becomes essential not to change the elevation of the carriage frame while a carton is being processed. The acceptance of this design hypothesis produces a corollary hypothesis, namely, that when the next succeeding carton is of a different height from the carton just admitted to the main conveyor, the succeeding carton must be retained at the gate until the previously admitted carton has been fully processed and has left the main conveyor. It also follows that the admission of a carton onto the main conveyor must be inhibited at any time when the carriage frame is being raised or lowered, since it is essential that when the carton is admitted the carriage frame be at exactly the right height to receive and process that particular carton.

In the presently preferred application of the invention to the sealing of the tops of cartons, the sealing operation requires at least one static device (gluing head) associated with the carriage frame, and also at least one movable device (rotary flap holding heads) associated with the carriage frame. Synchronizing the movement of each carton by the main conveyor with the movement of the movable sealing device therefore becomes a necessity. Dogs or cleats are provided on the main conveyor not merely for driving power to push each carton through the machine, but also for this important time synchronization. Furthermore, it becomes essential to admit each carton through the gate at exactly the proper time, so that its reception by the main conveyor will be timed in such manner as to be properly picked up by the next pair of dogs or cleats. This timed control is necessary in order

to achieve the high operating speed of the present illustrated form of the machine and also achieve the proper synchronization with the rotary flap folding heads.

Bearing in mind the essential characteristics of the machine and its operations as outlined above, the circuitry and operation of the electrical control system can be simply explained by reference to the terminology and techniques that are commonly employed in the analysis of digital computer circuits. See for example, "Arithmetic Operations in Digital Computers," R. K. Richards, D. Van Nostrand Company, Inc., 1955. In accordance with conventional computer techniques the various input signals for the control network are defined, the various output signals are defined, and the circuitry of the control network is then derived by the use of Boolean algebra. The first task, therefore, is to define the input and output signals, and correlate them to the physical apparatus, for which purpose reference is made to the following table:

TABLE I.—ELECTRICAL CONTROL SIGNALS

	Defined	Apparatus
Input Signal:		
W	A carton is waiting.....	Switch 122.
H	A high carton is waiting.....	Sensing means 120.
U	The carriage frame is up.....	Switch 117.
Q	The main conveyor is occupied.	Sensing means 264.
T	The time is right for next pair of main conveyor cleats.	Switch 206; cam 210.
Output Signal:		
O	Open gate to admit carton.....	Valve 204.
R	Raise carriage frame.....	Valve 245a.
L	Lower carriage frame.....	Valve 245a.

It is advisable to explain the manner in which the output signals are utilized. The gate 166 is normally biased to an extended or a closed position, as previously explained, so as normally to inhibit the entrance of a carton onto the main conveyor 113b. When the output signal "O" has a "1" or "true" value, then the gate valve 204 will be actuated so as to momentarily retract or open the gate. The momentary opening of the gate will permit the waiting carton to pass through the gate.

The raising and lowering of the carriage frame 114 is a somewhat more complicated problem. A conventional control is utilized, including the hoist valve 245a and high and low position contacts in the carriage frame sensing switch 117. It should properly be considered, therefore, that the carriage frame has its own separate control system for the purpose of continuing the movement of the carriage frame to either its high position or its low position once that movement has been initiated. In other words, the main electrical control system (soon to be described) initiates the signal to raise or lower the carriage, but a small separate control system associated with the carriage is operative to detect when the extreme limit of desired movement has been reached, and to correspondingly shut off the power to the hoist valve. Such controls are of course entirely conventional and do not require further detailed discussion.

From the standpoint of the computer logical analysis, however, it is significant to note that the gate will remain closed at all times except when its opening is positively initiated by the output signal. With regard to the carriage frame, it is necessary to consider the possibilities of the carriage frame being in its high position, in its low position, or in process of moving either up or down. In the presently illustrated embodiment of the invention the presence of the carriage frame in its high position is indicated by the closing of the high position contacts in the carriage frame position sensing switch 117; and the presence of the carriage frame in its low position is indicated by the closing of the low position contacts in the latter switch.

In the ensuing circuit analysis the Boolean algebraic notation is utilized, wherein a bar over a letter indicates the binary complement of the principal signal. Thus the signal W is considered as having a "1" or "true" value high position or the low position. For present purposes signal $\bar{W}$ is considered as having a "1" or "true" value

when no carton is waiting in the gate. In like manner the signal H has a "1" or "true" value when a high carton is waiting in the gate, while the signal $\bar{H}$ has a "1" or "true" value when no high carton is waiting in the gate. Since as previously pointed out the carriage frame has three separate conditions (high position, low position, or moving), there should theoretically be two binary signals to describe a condition of the carriage frame. However, one of the premises of the machine is that no carton will be admitted when the carriage frame is moving either up or down. Therefore, it is only necessary to sense the high position or the low position. For present purposes the signal U is utilized for both of these conditions; that is, the primary signal U has a "1" or "true" value when the carriage frame is in the high position, while the complementary signal $\bar{U}$ has a "1" or "true" value when the carriage frame is in its low position.

The signal Q is true when the main conveyor is occupied with a carton, as would be indicated by interruption of the light beam associated with sensing means 264. When the conveyor is not occupied the complementary signal $\bar{Q}$ has its "1" or "true" value. Signal T is a timing signal generated by delay device 206, 210, in conjunction with the gate, to delay the opening of the gate until the carton will be properly received by the next pair of conveyor dogs.

Having thus generally described the control system and its manner of operation, it is now possible to write Boolean algebraic equations which express the conditions when the output signals O, R, and L are to have "1" or "true" values:

(Equation 1)

$$O = (H \cdot U + W \cdot \bar{H} \cdot \bar{U}) \cdot T$$

(Equation 2)

$$R = H \cdot \bar{U} \cdot \bar{Q}$$

(Equation 3)

$$L = W \cdot \bar{H} \cdot U \cdot \bar{Q}$$

The above equations may be derived by constructing a permutation table representing the various possible operating conditions of the apparatus. Such a table is set forth below:

TABLE II.—OPERATING CONDITIONS

Rule	Inputs Present				Outputs Desired					
	W	H	Q	U	L	$\bar{L}$	R	$\bar{R}$	O	$\bar{O}$
1	W	H	Q	U		X				
2	W	H	$\bar{Q}$	$\bar{U}$					X	
3	W	H	$\bar{Q}$	U				X		
4	W	H	Q	U			X			
5	W	$\bar{H}$	Q	U				X		
6	W	$\bar{H}$	Q	$\bar{U}$			X			
7	W	$\bar{H}$	$\bar{Q}$	U	X				X	
8	W	$\bar{H}$	$\bar{Q}$	$\bar{U}$			X			
9-12	W	H			X		X			

The signal T does not need to be included in this table since it represents only a necessary timing function and not an independent condition.

A condition $\bar{W} \cdot H$ is an impossible condition, since if a high carton is present there is a carton present. Therefore, the last line in the table represents only four rules 9 through 12 inclusive, rather than eight rules 9 through 16 inclusive. One of the hypotheses of the present design of the apparatus illustrated herein is that, when no carton is waiting to be admitted through the gate, raising or lowering of the carriage frame is undesirable. This conclusion is expressed by rule 9-12 of Table II.

In the drawings, FIGURE 27 is a schematic circuit diagram of the control circuit actually used in the presently preferred form of the automatic carton handling machine of the present invention. FIGURE 28 represents an alternate form of the control circuit, which may be mechanized using conventional computer gating circuitry.

It will be recognized by those skilled in the computer art that the circuitry of FIGURE 28 has a one-to-one correspondence with the Equations 1, 2 and 3 set forth above.

Referring to FIGURE 27, it will be seen that a separate relay is used to generate each of the control or input signals H, U, and Q. In the case of input signal H in particular, the relay may have four separate outputs as illustrated. Two of the outputs (the two boxes designated H) will provide closed or continuous circuits when a high carton is waiting in the gate; while the other two outputs (those designated as $\bar{H}$) will provide a continuous or closed circuit when no high carton is waiting in the gate. While the control signal U is represented as having four separate relay outputs, in the actual embodiment of the invention as herein illustrated and described, the signal U is provided by the high position contacts in the carriage frame sensing switch 117, while the signal $\bar{U}$ is provided by the low position contacts of the latter switch. The signal $\bar{Q}$ is provided in each case by the photocell 268, when the main conveyor is not occupied and that photocell receives the associated light beam that is intended for it.

While particular forms of the electrical control circuit are illustrated herein, it will be understood that other equivalent forms thereof may be utilized without departing from the present invention or from the scope of the appended claims. In particular, the invention as presently illustrated provides for the handling of only two predetermined heights of cartons; however, the invention comprehends the possibility of using cartons of three or more different heights, all in accordance with the basic organization and mode of operation of the automatic carton handling machine as herein disclosed. Thus if cartons of three predetermined heights are to be utilized, the input signals W and H are supplemented by a third separate input signal. In that situation the signal W indicates the presence of a carton, which could be a low carton; the signal H_1 indicates the presence of a high carton; and the presence of signal H_2 indicates the presence of a still higher carton. If four different heights of cartons are utilized, it would be desirable if perhaps not absolutely necessary to add still another sensing device, providing still another separate input signal, for the purpose of indicating the presence of such a higher carton. Of course, if more than two heights of cartons are to be handled, the presently illustrated control system for raising and lowering the carriage frame must be modified, in order to provide intermediate stopping points as well as the stopping points at the extreme end of travel locations. Such modifications are within the skill of the art and are comprehended as being within the scope of this invention and the appended claims.

Résumé of machine operation

It is now evident that the incoming high cartons A and low cartons A' enter the present carton sealing machine 100 at the left hand, infeed end of the main machine frame 102. Each entering carton is transported through the sensing station 104, by the infeed conveyor 113a, to a position against the currently extended gate stop 166, where the carton is momentarily arrested. Upon arrival at this position, the carton actuates the sensing switch 122 to indicate that a carton is present at the sensing station. During entrance of the carton into the sensing station, the bottom wall of the carton is engaged by the drag shoe 190 which effects rotation of the carton to the phantom line position of FIGURE 3a, wherein the leading corner of the carton, adjacent the guide rail 156, engages the inner guiding surfaces 164 of this rail in advance of the gate stop 166. This assures engagement of each entering carton with the gate stop.

The carton height sensing means 120 senses the height of each incoming carton. This sensing means generates a high signal in response to each incoming high carton A and a low signal in response to each incoming low carton

A'. If the current vertical position of the carriage frame 114 does not correspond to the height of the waiting carton currently at the gate stop 166, the control circuit of the machine is activated to effect adjustment of the carriage frame to the vertical position corresponding to the waiting carton. Arrival of the carriage frame at this position is signalled by closing of the high contacts or the low contacts, as the case may be, of the carriage frame position sensing switch 117. Closing of these switch contacts conditions the control circuit of the machine to effect retraction of the gate stop 166 in response to actuation of the gate stop switch 206 by the cam 210 on the main conveyor shaft 142. This cam periodically actuates the switch 206 in timed relation to the movement of the main conveyor chains 140, and, therefore, in timed relation to the rotary motion of the rotary flap folding heads 278 at the following station 106. Gate stop 166, therefore, is retracted to release the waiting carton for movement by the infeed conveyor 113a unto the main conveyor 113b, at the proper time to effect arrival of the carton on the main conveyor slightly in advance of the following drive cleats 146 on this conveyor. As the carton moves from the sensing station 104, the carton is urged against the guide rail 154 and thereby aligned, laterally of the machine, relative to the operating means 124 in the following, main operating section of the machine.

The main conveyor 113b now conveys the carton through this main operating section. As the carton travels through the end flap opening side flap closing station 106, the carton end flaps F are initially folded outwardly to their horizontal gluing positions and, thereafter, its side flaps E are folded inwardly to their closed positions by the rotary flap folding heads 278. The flap folding operation of these heads is best depicted in FIGURES 26-1 through 26-4. FIGURE 26-1 illustrates a flap folding head approaching its initial position of end flap folding engagement with an incoming carton. At this time, the end flap folding shoe 320 on the head is elevated to clear the leading side flap of the carton and is just commencing to descend to its lower extended position, wherein the shoe is disposed for laterally outward folding engagement with the adjacent carton end flap. FIGURE 26-2 illustrates the flap folding head in its initial position of outward folding engagement with the adjacent carton end flap. During rotation of the head from its position of FIGURE 26-2 to its position of FIGURE 26-3, the end flap folding shoe on the head rotates the adjacent carton end flap outwardly to its horizontal gluing position of the latter figure. Continued rotation of the head brings the latter to the following position of FIGURE 26-4, wherein the side flap folding shoe 318 on the head is disposed in forward folding engagement with the trailing side flap E of the carton. Continued rotation of the head now folds this trailing side flap forwardly to its closed position over the top opening of the carton and effects elevation of the end flap folding shoe 320 to its retracted position, wherein this shoe is disposed to clear the leading side flap of the following carton.

After emerging from the station 106, the carton enters the gluing station 108. During movement of the carton through this station, its outwardly folded end flaps F receive the hot and cold glue stripes S_h and S_c from the hot and cold glue applicators 370, 372. Final movement of the carton then occurs through the end flap closing station 110, wherein the end flap closing means 130 are effective to rotate the adhesively coated carton end flaps upwardly and inwardly to their closed positions of adhesive bonding engagement with the previously closed carton side flaps. Thereafter, the carton emerges from the machine through the compression station 112, wherein the compression rollers 400 retain the closed end flaps in their closed positions sufficiently long for the hot glue to set.

During passage of each carton through the main operating section 100a of the machine, the carton intercepts

the light beam from the light source 266 of the sensing means 264. This action inhibits vertical adjustment of the carriage frame 114, to accommodate a following carton of different height, until the preceding carton is clear of the operating section.

It is now obvious, therefore, that the invention herein described and illustrated is fully capable of attaining the several objects and advantages preliminarily set forth.

While the presently preferred embodiment of the invention has been disclosed for illustrative purposes, it is obvious that various modifications in the design, arrangement of parts, and instrumentalities of the invention are possible within this spirit and scope of the following claims.

What is claimed as new in support of Letters Patent is:

1. An infeed gate mechanism for a carton handling machine including a frame having infeed and outfeed ends, and conveyor means on said frame for successively transporting cartons to be handled along said frame from said infeed end to said outfeed end with given sides of each carton extending laterally of said frame, said gate mechanism comprising:

a pair of guide rails extending lengthwise of said infeed end of said frame at opposite sides of said conveyor means to receive therebetween the entering cartons, one of said rails having a predetermined location laterally of said frame and being adapted to locate each entering carton laterally of said frame, a gate stop mounted on said frame adjacent the other rail for movement laterally of said frame between an inner guiding surface of said other rail for engagement with the adjacent leading corner of each entering carton to arrest the latter and an outer retracted position wherein said stop is disposed to clear the entering cartons for movement of the latter along said frame by said conveyor means, and means for effecting extension and retraction of such stop in such manner that said stop remains retracted for an interval of time less than the time required for each entering carton to travel past the stop, whereby said stop is effective to urge each entering carton against said one rail.

2. An infeed gate mechanism according to claim 1 wherein:

each entering carton has a first dimension measured between said given sides thereof and a second dimension measured between its remaining sides, the spacing between said rails being greater than said second dimension of each entering carton, retarding means mounted on said frame adjacent said other rail in advance of said stop relative to the direction of movement of said cartons along said frame, and said retarding means being disposed for retarding engagement with each entering carton, whereby said retarding means is effective to rotate each entering carton to a position wherein said leading corner of the respective carton engages the inner guiding surface of said other rail in advance of said stop.

3. An infeed gate mechanism according to claim 2 wherein:

the inner guiding surface of said one rail has a leading portion adjacent the infeed end of said frame and a following trailing portion, the spacing between said trailing portion and said other rail being greater than the spacing between said leading portion and said other rail and substantially greater than said second dimension of each entering carton, the junction of said leading and trailing portions being located in advance of said stop relative to the direction of movement of said cartons along said frame, and said stop when substantially fully extended being effective to position each entering carton in guiding relation to said trailing portion of the guiding surface of said one rail, whereby said stop is disposed

to engage the following carton before the previous carton has cleared said stop.

4. An infeed gate mechanism according to claim 3 including:

resilient camming means mounted on said other rail a distance beyond said stop relative to said direction of carton movement for urging each entering carton against said trailing portion of said guiding surface of said one rail.

5. An infeed gate mechanism according to claim 1 wherein:

each entering carton has a first dimension measured between said given sides thereof and a second dimension measured between its remaining sides, the inner guiding surface of said one rail has a leading portion adjacent the infeed end of said frame and a following trailing portion, the spacing between said other rail and each of said leading and trailing portions is greater than said second dimension of each entering carton, the spacing between said trailing portion and said other rail is greater than the spacing between said leading portion and said other rail, the juncture of said leading and trailing portions is located between the leading ends of said rails and said stop, the spacing between said juncture and stop measured lengthwise of said frame is less than said first dimension of each entering carton, retarding means mounted on said frame adjacent said other rail and laterally opposite said leading portion of said guiding surface of said one rail, said retarding means being disposed for retarding engagement with each entering carton, whereby said retarding means is effective to rotate each entering carton into a position wherein said leading corner thereof engages the inner guiding surface of said other rail in advance of said stop, and resilient camming means mounted on said other rail beyond said stop relative to said direction of carton movement for urging each entering carton against said one rail.

6. An infeed gate mechanism according to claim 1 wherein:

said means for effecting extension and retraction of said stop comprises a cylinder containing a piston having a rod extending from one end of said cylinder and connected at its outer end to said stop, means pivotally mounting said cylinder on said frame for movement of said stop lengthwise of said frame, means for selectively pressurizing said cylinder to effect extension and retraction of said stop, means for urging said stop lengthwise of said frame toward said infeed end, and yieldable means operatively connected between said frame and stop for resisting movement of said stop lengthwise of said frame towards said outfeed end, whereby said stop when extended is effective to progressively arrest each entering carton.

7. An infeed gate mechanism for a carton handling machine including a frame having infeed and outfeed ends, and conveyor means on said frame for successively transporting cartons to be handled along said frame from said infeed end to said outfeed end, said gate mechanism comprising:

a gate stop, a cylinder containing a piston having a rod extending from one end of said cylinder and connected at its outer end to said stop, means pivotally mounting said cylinder on said frame for movement of said stop lengthwise of said frame, means including a fluid pressure system for selectively pressurizing said cylinder to effect movement of said stop between an extended position wherein said stop is disposed for arresting engagement with each entering carton and a retracted position wherein said stop is disposed to clear the entering cartons for movement along said frame by said conveyor means, means for urging said stop lengthwise of said frame

towards said infeed end, and dashpot means operatively connected between said frame and said stop for resisting movement of said stop lengthwise of said frame towards said outfeed end, whereby said stop is adapted to progressively arrest each entering carton.

8. In a machine for closing and sealing cartons each having an open side bounded by hinged, generally erect side and end flaps with outer and inner surfaces adapted to be folded to overlapping closed positions wherein the flaps close said open side and said end flaps overlie said side flaps with their inner surfaces contacting the outer surfaces of said side flaps, the combination comprising:

a frame having infeed and outfeed ends, conveyor means on said frame for successively transporting said cartons along said frame from said infeed end to said outfeed end with said side flaps of each carton facing generally lengthwise of said frame, there being a flap folding station along said frame through which each carton travels, power driven cyclically movable flap folding means mounted on said frame within said station and over said conveyor means for successively engaging the end flaps and trailing side flap of each carton traveling through said station in such manner as to initially fold the end flaps of the respective carton laterally outwardly to gluing position wherein the latter flaps are disposed laterally outwardly of the adjacent ends of the side flaps on the respective carton and thereafter fold the trailing side flap of the respective carton forwardly to its closed position over the open side of the carton, side flap closing means mounted on said frame over said conveyor means following said folding means relative to the direction of travel of said cartons along said frame for folding the leading side flap of each carton traveling through said station rearwardly to its closed position over the open side of the respective carton after folding of the end flaps of the respective carton to said gluing positions, end flap closing means on said frame following said folding means for folding said end flaps of each carton to their closed positions of overlapping engagement with the side flaps of the respective carton, and means for driving said conveyor means and folding means in timed relation in such manner as to effect successive movement of said cartons through said station in timed relation to the cyclic movement of said folding means.

9. A carton closing and sealing machine according to claim 8 including:

glue applicators on said frame following said folding means for applying glue to the inner surfaces of the end flaps of each carton emerging from said folding means while the latter flaps occupy such gluing positions thereof.

10. A carton closing and sealing machine according to claim 8 including:

hot and cold glue applicators on said frame between said folding means and end flap closing means for applying stripes of hot and cold glue to said end flap inner surfaces of each carton.

11. A carton closing and sealing machine according to claim 8 wherein:

said flap folding means comprise a pair of rotary flap folding heads spaced laterally of said frame and rotatably mounted on said frame for turning through initial positions of laterally outward folding engagement with the end flaps of each carton traveling through said station and following positions of forward folding engagement with the trailing side flap of the respective carton, and means for rotating said folding heads in unison in such manner that said heads rotate through said initial and following positions simultaneously.

12. A carton closing and sealing machine according to claim 8 wherein:

said flap folding means comprise a pair of rotary flap folding heads spaced laterally of said frame and rotatably mounted on said frame for turning on generally vertical axis through initial positions of laterally outward folding engagement with the end flaps of each carton traveling through said station and following positions of forward folding engagement with the trailing side flap of the respective carton, and means for rotating said heads in unison in such manner that said heads rotate through said initial and following positions simultaneously.

13. A carton closing and sealing machine according to claim 12 wherein:

said folding heads each comprise a side flap folding shoe and a diametrically opposed end flap folding shoe which are generally circularly curved about the rotation axis of the respective folding head, whereby said machine comprises a pair of end flap folding shoes and a pair of side flap folding shoes, said heads are driven in opposite directions of rotation in such manner that the shoes of each of said shoe pair travel in unison through the region between said heads and move in the direction of said outfeed end within said region, said end flap folding shoes are disposed to engage the inner surfaces of said end flaps of each carton passing through said station and urge the latter flaps outwardly to said gluing positions during rotation of said folding heads through said initial positions, and said side flap folding shoes are disposed to engage the outer surface of said trailing side flap of each carton traveling through said station and urge the latter flap forwardly to its closed position during rotation of said folding heads through said following positions.

14. A carton closing and sealing machine according to claim 13 wherein:

said end flap folding shoes are mounted on said folding heads for generally axial movement relative to said heads between upper retracted positions wherein said latter shoes are disposed to clear the erect leading side flap on each carton passing through said station and lower extended positions wherein the latter shoes are disposed for folding engagement with said end flaps of each carton passing through said station, and means for effecting extension and retraction of said end flap folding shoes in timed relation to rotation of said folding heads in such manner that said latter shoes are extended substantially only during rotation of said folding heads through said initial positions.

15. In a machine for handling cartons of differing size which are delivered in random sequence to the machine and wherein certain machine operations are controlled in response to the size of each entering carton, the combination comprising:

a frame having a sensing station at which the size of each incoming carton is sensed, conveyor means on said frame for successively transporting said cartons along said frame and through said station, and sensing means at said station for sensing the size of each carton passing through said station including a light source for directing a beam of light along the optic axis of said source, a photo-sensitive receiver having a sensitive axis, and means mounting said source and receiver on said frame at the same side of the path of movement of said cartons through said station with said axes of said source and receiver intersecting at a predetermined position along said path in such manner that light from said source is reflected to said receiver by cartons of a given size only during passage of each carton of said given size through said station.

16. A carton handling machine according to claim 15 wherein:

said cartons comprise relatively high cartons and relatively low cartons each having generally erect relatively high side flaps and relatively low end flaps, each carton travels along said frame with its end flaps facing laterally of said path, said machine comprises means for closing and sealing said flaps of each carton and means responsive to said sensing means for adjusting the elevation of said carton closing and sealing means relatively to said conveyor means in accordance with the height of each incoming carton, the height above said conveyor means of the upper edges of the high carton end flaps is greater than the corresponding height of the upper edges of the low carton end flap, and said light source and receiver are mounted in such manner that light from said source impinges and is reflected to said receiver from the adjacent end flap of each high carton only passing to said station.

17. A carton handling machine for successively operating on relatively high cartons and relatively low cartons of predetermined heights which are delivered to the machine in random sequence, the combination comprising:

a main frame, conveyor means on said frame for successively transporting said cartons along said frame, a vertically adjustable carriage frame over said main frame, operating means on said carriage frame for operating on each carton passing along said main frame, sensing means on said main frame in advance of said carriage frame for sensing the height of each incoming carton and generating a high signal in response to each incoming high carton and a low signal in response to each incoming low carton, and elevating means responsive to said sensing means and operatively connected between said frames for selectively vertically driving said carriage frame to a pre-set height position wherein said operating means are disposed to operate on said high cartons in response to each said high signal and driving said carriage frame to a pre-set low position wherein said operating means are disposed to operate on said low cartons in response to each said low signal.

18. A carton handling machine according to claim 17 wherein:

said elevating means comprise a pair of parallel crank shafts rotatably mounted on one frame and having eccentric crank ends rotatably mounted in the other frame, whereby unified rotation of said crank shafts is effective to vertically move said carriage frame between said pre-set positions, sprockets on said shafts, flexible power transmission means trained about said sprockets, and power means mounted on said frame and operatively connected to said power transmission means for driving the latter means to a limiting position in one direction to elevate said carriage frame to said high position and driving said power transmission means to a limiting position in the opposite direction to lower said carriage frame to said low position.

19. A carton handling machine according to claim 17 wherein:

said elevating means comprise a pair of parallel crank shafts extending laterally of and rotatably supported on said main frame below said carriage frame and having eccentric crank ends at their outward ends rotatably supported in said carriage frame, whereby unified rotation of said crank shafts is effective to vertically move said carriage frame between said pre-set positions, and power means on said main frame operatively connected to said crank shafts for rotating said shafts in unison to elevate and lower said carriage frame.

20. A carton handling machine for automatically per-

forming an operation on a series of cartons of differing height which are delivered to the machine in random sequence, comprising:

a main frame having a sensing station and an operating station spaced therealong, conveyor means on said frame for successively transporting said cartons along said frame thru said sensing station and thereafter thru said operating station, a vertically adjustable carriage frame at said operating station, operating means on said carriage frame for operating on each carton passing through said operating station, elevating means for raising and lowering said carriage frame to vertically position said operating means for operating on cartons of different height, first sensing means at said sensing station for sensing the height of each incoming carton, second sensing means for sensing the elevation of said carriage frame, means for controlling the movement of each carton from said sensing station to said operating station, and a control circuit operatively associated with said elevating means, said sensing means, and said controlling means for effecting vertical adjustment of said carriage frame to an elevation corresponding to the height of each carton sensed by said first sensing means and inhibiting movement of each carton from said sensing station to said operating station when the elevation of said carriage frame does not correspond to the height of the respective carton.

21. A carton handling machine according to claim 20 wherein:

said conveyor means operates continuously, said controlling means comprises an infeed gate movable between an extended position wherein said gate is disposed to arrest each carton at said sensing station and a retracted position wherein said gate is disposed to release the respective carton for movement from said sensing station to said operating station, and said control circuit is effective to inhibit retraction of said gate and thereby retain each carton at said sensing station when the elevation of said carriage frame does not correspond to the height of the respective carton.

22. A carton handling machine according to claim 20 including:

third sensing means at said sensing station for sensing the presence of a carton at said sensing station, and said control circuit being operatively associated with said third sensing means to inhibit vertical adjustment of said carriage frame when said sensing station is not occupied by a carton.

23. A carton handling machine according to claim 20 including:

third sensing means for sensing the presence of a carton within said operating station, and said control circuit being operatively associated with said third sensing means to inhibit vertical adjustment of said carriage frame wherein said operating station is occupied by a carton.

24. A carton handling machine according to claim 20 wherein:

each set carton has generally erect side and end flaps, said operating means comprise means including cyclically movable power driven flap folding means for closing and sealing the flaps of each carton passing through said operating station, and said control circuit is operatively associated with said flap folding means to effect operation of said controlling means in timed relation to the cyclic movement of said folding means, thereby to cause movement of each carton through said operating station in timed relation to said cyclic movement.

25. A carton handling machine for automatically performing an operation on the tops of a series of cartons of differing predetermined heights, comprising:

an elongated frame;

a continuously moving conveyor on said frame; a carriage disposed above said frame; means associated with said carriage for performing said operation;

a gate for controlling entry of cartons onto said conveyor;

sensing means cooperatively associated with said gate for sensing whether a carton is waiting to pass through said gate, and if so, the particular predetermined height category to which said waiting carton belongs;

means for selectively raising or lowering said carriage relative to said frame so as to successively accommodate cartons of different heights;

means for sensing whether said conveyor is occupied by a carton;

and control circuit means cooperatively associated with said gate, said sensing means, said raising or lowering means, and said means for sensing, said control circuit means being operative for inhibiting the raising or lowering of said carriage while said conveyor is occupied, for inhibiting the admission of a carton through said gate while said carriage is being raised or lowered, and for inhibiting the admission of a carton through said gate when the height of a waiting carton does not correspond to the existing elevation of said carriage;

said control circuit means being also operative when said conveyor is not occupied and a carton is waiting to pass through said gate, for changing the elevation of said carriage if the existing elevation thereof does not correspond to the height of the waiting carton.

26. A carton handling machine as defined in claim 25 wherein said operation is a sealing operation, and said machine includes a sealing device movably associated with the underside of said carriage, and means for drivingly actuating said movable sealing device in synchronism with the movement of said conveyor; said conveyor being adapted to accept cartons from said gate only at predetermined periodic times.

27. A carton handling machine as defined in claim 26 wherein said conveyor includes a pair of chains having corresponding pairs of dogs spaced at equal longitudinal intervals therein, said dogs being operative both for providing driving power to the cartons and also for synchronizing the movement of the cartons with the actuation of said movable sealing device.

28. A carton handling machine as claimed in claim 26 wherein said movable sealing device is a flap folding means.

29. A carton handling machine as defined in claim 26 which further includes a gluing head statically associated with the underside of said carriage.

30. A carton handling machine as defined in claim 27 which further includes a cam switch cooperatively associated with said gate for selectively opening said gate in synchronism with the movement of a pair of said conveyor dogs.

31. A carton handling machine as defined in claim 25 wherein said sensing means includes a mechanical device operative to detect the presence of a carton waiting to pass through said gate, and a photoelectric device operative to determine whether the height of a waiting carton exceeds a predetermined height.

32. A carton handling machine as defined in claim 25 wherein said means for sensing whether said conveyor is occupied by a carton is a photoelectric device which includes means for transmitting a light beam above said conveyor longitudinally thereof.

33. In a carton handling machine, the combination comprising:

a frame, conveyor means on said frame for successively transporting said cartons along said frame, and photo-sensitive means for sensing the presence of a carton on said conveyor means including a light source for

33

directing a light beam lengthwise of said conveyor means within the path of movement of each carton along said frame by said conveyor means and the photosensitive receiver for receiving said light beam after the latter has traveled the length of said conveyor means.

34. A carton handling machine according to claim 33 wherein:

said light source is located adjacent one end and one side of said conveyor means, said receiver is located adjacent the opposite end and at the opposite side of said conveyor means, and said light beam

5

34

travels diagonally across said conveyor means from said light source to said receiver.
